UNITED STATES PATENT OFFICE.

JOSHUA B. BARNES, OF SPRINGFIELD, ILLINOIS.

CAR-TRUCK.

No. 820,337.

Specification of Letters Patent.

Patented May 8, 1906.

Application filed January 22, 1906. Serial No. 297,288.

To all whom it may concern:

Be it known that I, JOSHUA B. BARNES, a citizen of the United States, residing at Springfield, in the county of Sangamon and State of Illinois, have invented a new and useful Improvement in Car-Trucks, of which the following is a specification.

My invention relates particularly to a freight-car truck having a cast-steel or other truck-bolster, and has for its object to simplify the construction and to obtain a strong, light, and rigid structure.

The invention consists in features of novelty, as hereinafter described and claimed, reference being had to the accompanying drawings, forming part of this specification, whereon—

Figure 1 is a top plan view of my improved car-truck omitting the brakes and other appendages of ordinary well-known construction; Fig. 2, a side elevation thereof to enlarged scale, and Fig. 3 a vertical longitudinal section through one-half of the truck-bolster and combined side frame of the truck on line 33 in Fig. 1.

Like letters and numerals of reference denote like parts in all the figures.

a represents the truck-bolster, which is preferably metallic, of any suitable design, having the usual center plate 1, side bearings 2, and guide-lugs 3. Each side frame of the truck comprises the arch-bar *b*, the inverted arch-bar *c*, having the truck-columns *d* as component parts thereof, and the bottom tie-bar *e*, which are secured together by the bolts 4, the bars *b*, *c*, and *e* spanning and supporting the axle-boxes *f*, to which they are secured by the bolts 4' in the usual manner.

In lieu of the separately-constructed bolster guide-bars or truck-columns and spring-plank with their separate attachments to the arch-bars and transoms, respectively, as ordinarily used, I make the inverted arch-bar *c*, preferably of cast-steel, having the truck-columns *d* integral therewith, the lower middle portion of the inverted arch-bar *c* having lateral flanges or extensions 5, which are flush with the top side of the bar *c* thereat and form therewith a seat 6 for the bolster-springs 7, the flanges 5 being united integrally to the preferably-cored body of the bar *c* beneath the seat 6 by ribs 8, as shown. The top of the truck-columns *d* and outer end portions of the inverted arch-bar

c, where they bear on the axle-boxes *f*, are preferably channeled for receiving the arch-bar *b*, while the bottom of the middle portion of the inverted arch-bar *c*, beneath the spring-seat 6, is similarly channeled for receiving the bottom tie-bar *e*. The truck-columns *d* of one side frame are secured to the columns *d* of the other side by the transoms *g*, which in the present case are preferably angle-irons extending between the side frames of the truck, one on each side of the bolster *a*, in the usual manner, their end portions being fixed by rivets (or bolts) 9 to correspondingly-shaped brackets 10, which are formed, respectively, on the rear side of each column *d* integrally therewith and at a suitable distance above the bolster spring-seat 6, each bracket 10 preferably projecting longitudinally beyond the sides of the column *d* for insuring an extended bearing 75 and rigid connection thereto of the transoms *g*, or the transoms *g* may be secured to the columns *d* in any other suitable manner or directly to the inverted arch-bar *c*. To each transom *g* are coupled the brake-hangers 11, as shown in Fig. 2, the brakes and other appendages of the truck (not shown) being of the ordinary well-known construction and needing no further description.

By making the truck-columns *d* and bolster spring-seats 6 integral with the inverted arch-bars *c* the separately-constructed truck-columns, with their fastenings, are superseded and simplified and the spring-plank dispensed with, whereby the truck is rendered more rigid and durable, and by eliminating the ordinary fastenings of these hitherto separately-constructed parts an element of danger from their loosening and fracture is removed. Moreover, by the strength and rigidity of the integral inverted arch-bar and truck-columns, combined with the rigid fastenings thereto of the transoms *g* to the columns *d* at a certain distance above the spring-seat 6, increased steadiness and stability are imparted to the truck, relative thereto it is here noted that the columns *d* are united integrally to the upwardly and outwardly inclined portions of the inverted arch-bar *c* immediately beneath the brackets 10 by horizontal tie-pieces 12 for insuring additional strength to the casting thereat, the said inclined portions being preferably channel or U-shaped in cross-section, as shown, or otherwise as found most suitable.

What I claim as my invention, and desire to secure by Letters Patent, is—

1. In a car-truck, the combination with the truck-bolster and axle-boxes, of side frames comprising respectively an arch-bar, an inverted arch-bar consisting of an integral casting having the truck-columns and bolster spring-seat integral therewith, and a bottom tie-bar, means for fixing the said bars and axle-boxes together, and transoms connecting the side frames to each other at a suitable distance above the said seat, substantially as described.
2. In a car-truck, the combination with the truck-bolster, the transoms, and the axle-boxes, of side frames comprising respectively an arch-bar, an inverted arch-bar consisting of an integral casting having the truck-columns and bolster spring-seat integral there-
3. In a car-truck, an inverted arch-bar consisting of an integral casting having the truck-columns and bolster spring-seat integral therewith, the said bar being channeled at the top and bottom, substantially as described.

with, brackets integral with the truck-columns at a suitable distance above the said seat and adapted for the attachment thereto of the transoms, and means for fixing the said bars and axle-boxes together, substantially as described.

25

3. In a car-truck, an inverted arch-bar consisting of an integral casting having the truck-columns and bolster spring-seat integral therewith, the said bar being channeled at the top and bottom, substantially as described.

30

In testimony whereof I have signed my name to this specification in the presence of two subscribing witnesses.

JOSHUA B. BARNES.
